UNITED STATES PATENT OFFICE

FREDERICK T. MOORE, OF EAST HARTFORD, CONNECTICUT, ASSIGNOR TO COLT'S PATENT FIRE ARMS MANUFACTURING CO., OF HARTFORD, CONNECTICUT, A CORPORATION OF CONNECTICUT

COOLING SYSTEM FOR FIREARMS

Application filed May 14, 1931. Serial No. 537,283.

The present invention is particularly applicable to automatic firearms of the type disclosed in patents to John M. Browning No. 1,293,021 dated February 4, 1919 and No. 1,628,226 dated May 10, 1927; but the invention is not necessarily so limited.

When an automatic firearm of the type shown in the aforesaid patents is intended for ground or field use, it is commonly provided with a water tube or jacket which surrounds the barrel, water being circulated through the jacket to cool the barrel. The jacket has the further function of supporting and guiding the barrel near the forward end thereof. For aeroplane use and also for purposes including some classes of ground service, the water jacket may be omitted and there may be provided in lieu thereof a smaller jacket which surrounds the barrel and serves to support and guide the barrel near the forward end thereof. This smaller jacket is provided with openings therein which permit free circulation of air so that air cooling of the barrel will be effected.

The mechanisms of the water cooled and of the air cooled firearms may be identical or at least similar in construction, and one of the objects of the present invention is to provide means at the forward end of the main casing which makes it possible for the interchangeable attachment either of the parts required for water cooling or of the parts required for air cooling. As the result of the invention, it is possible to construct the various parts of the firearm properly without regard to the cooling system to be used, thus making it possible for the parts to be made in larger quantities, and therefore more economically. The invention has the further advantage that firearms originally constructed for one system of cooling can be easily transformed so as to be adapted for the other system. The complete equipment of a firearm may include parts for both water cooling and air cooling, thus making it possible for either system to be used that conditions may make necessary.

In the accompanying drawing I have shown the embodiment of the invention which I now deem preferable, but it will be under-

stood that the drawing is intended for illustrative purposes only and is not to be construed as limiting or defining the scope of the invention, the claims forming a part of this specification being relied upon for that purpose.

Of the drawing:

Fig. 1 is a side view of the front portion of an automatic firearm embodying the invention and having in place thereon the jacket 60 for water cooling.

Fig. 2 is a fragmentary detailed view partly in section along the line 2-2 of Fig. 1.

Figs. 3 and 4 are plan and side views respectively of the latch, of which an end view appears in Fig. 2.

Fig. 5 is a view similar to Fig. 1, but showing the jacket for air cooling substituted for the jacket for water cooling.

An automatic firearm or gun of the type to which the invention is particularly applicable, has a breech or main casing which carries and contains all of the working parts except the barrel which projects from the casing at the front thereof. In the drawing only the front portion of the casing is shown, this being indicated at 1. The barrel 2 projects forward from the breech or main casing and is mounted to reciprocate longitudinally during firing as fully explained in the two patents referred to. The main casing 1 includes a front end member 3 which is commonly known as a trunnion block. The trunnion block 3 is mounted between two side plates 4, 4 which are riveted to the trunnion block as indicated at 5, 5. A transverse hole 6 through the trunnion block and through the side plates is adapted for the reception of a transverse trunnion pin which forms a part of or is carried by the mount on which the gun is supported. This trunnion pin, by reason of its engagement with the trunnion block and side plates, serves to support the forward end portions of the gun.

Carried by the main casing at the forward end thereof is a means so constructed as to be adapted either for the attachment of a relatively large jacket for water cooling or for the attachment of a smaller jacket for air cooling. As concerns the broader aspects of

the invention, I do not limit myself as to the particular form of this attachment means, but preferably the said means is in the form of a forward projecting flange 7 surrounding the barrel 2 and secured to or formed as a part of the trunnion block 3. The flange 7 is exteriorly threaded at 8 for the attachment of a jacket for water cooling, and it is interiorly threaded at 9 for the attachment of a jacket 10 for air cooling.

In Fig. 1 I have shown in place a jacket for water cooling, this jacket being indicated as an entirety by 10. The jacket 10 is provided at its forward ends with the usual means for supporting and guiding the barrel 2. The details of the water jacket 10 and the parts used therewith constitute no part of the present invention and description of them can be omitted. At the rear end of the water jacket 10 there is provided an adapter member or cap 11 having a flange into which the rear end of the water jacket proper is threaded. The adapter member 11 has a cylindrical portion 11^a which surrounds and engages the flange 7 and is provided with internal threads which engage the external threads 8 on the said flange. The threads 8 are concentric with the barrel, and it will therefore be obvious that the adapter 11 with the jacket 10 can be put in place or removed by being rotated about the barrel axis so as to engage or disengage the threads at 8.

In order to locate the adapter 11 and the water jacket 10 in proper relationship to the other parts of the gun, the cylindrical portion 11^a of the adapter is provided at its rear end with a notch 12 into which enters a movable latch 13. The details of the latch 13 may be varied without departing from the invention, but as shown the latch is mounted between the two depending portions 3^a, 3^b of the trunnion block, being supported by a transverse pivot pin at 14. A spring pressed plunger 15 is adapted to enter a transverse horizontal hole 16 in one of the said depending portions 3^a, this plunger serving to hold the latch in its upper operative position. The plunger 15 can be withdrawn from the hole 16 by inserting a suitable tool into a hole 15^a in the plunger and by thus moving the plunger endwise against the pressure of its spring. When the plunger 15 is free from the hole 16, the latch may be swung downward to release the adapter 11.

It will be apparent that when the water jacket 10 is in place as shown in Fig. 1 the threads 9 for the other jacket intended for air cooling are not used, but the said threads 9 are nevertheless provided in order that the gun may be adapted to be very quickly and conveniently transformed from a water cooled gun to an air cooled gun.

In Fig. 5 I have shown the gun equipped for air cooling, and it will be understood that the trunnion block with the flange 7 thereon

is exactly the same as already described in connection with Fig. 1. The water jacket 10 and the adapter member 11 therefor are omitted, and there is provided a smaller jacket 17 which surrounds the barrel and which at its rear end enters and engages the interior of the flange 7. The jacket 17 has exterior threads which engage the interior threads 9 on the said flange. The jacket 17 is provided with a number of relatively large openings 18, 18 which facilitate the circulation of air into contact with the barrel, and the said jacket is further provided with means near its forward end for supporting and guiding the barrel 2.

Preferably when the jacket 17 is in place there is provided an auxiliary member 19 which is connected to and surrounds the flange 7, this member preferably having two functions. One of these functions is to cover and protect the external threads 8 on the flange 7, and the other of these functions is to serve as means for connecting the gun with the mount or other means on which it is supported. As already pointed out, the horizontal hole 6 through the trunnion block and the side plates of the breech casing may be used for receiving a trunnion pin which supports the forward portion of the gun; but for an air cooled gun it is sometimes preferred to provide a means of support at a position forward from the hole 6. Accordingly the connection member or ring 19 is provided with two depending lugs 20 spaced apart transversely. In these lugs are aligned transverse holes 21 which may be used to receive a horizontal trunnion pin or other means for connecting the gun with the mount or other structure upon which it may be supported. The connection member 19 is provided with a notch 22, similar to the notch 12 in the adapter 11, and this notch may be entered by the latch 13 in the manner already described to hold the member 19 in its proper predetermined relationship to the other parts of the gun.

What I claim is:

1. In an automatic firearm, a main casing having at the forward end thereof means comprising two separate portions adapted respectively for the attachment of two different interchangeable barrel jackets.

2. In an automatic firearm, a main casing having at its forward end a flange exteriorly threaded for the attachment of a barrel jacket and interiorly threaded for the attachment of a different barrel jacket.

3. For an automatic firearm, a trunnion block having at the front thereof an integral flange exteriorly threaded for the attachment of a barrel jacket and interiorly threaded for the attachment of a different barrel jacket.

4. In an automatic firearm, the combination of a main casing having at its forward end a flange surrounding the barrel and

adapted at its interior to receive and engage a barrel jacket for air cooling, an adapter member engaging the flange at the exterior thereof, and a water jacket for the barrel connected with the said adapter member.

5. In an automatic firearm, the combination of a main casing having at its forward end an exteriorly threaded flange surrounding the barrel, the said flange being interiorly threaded for the attachment of a barrel jacket for air cooling, an adapter member engaging the exterior threads of the flange, and a water jacket for the barrel connected with the said adapter member.

6. In an automatic firearm, the combination of a main casing having at its forward end an exteriorly threaded flange surrounding the barrel, the said flange being interiorly threaded for the attachment of a barrel jacket for air cooling, an adapter member engaging the exterior threads of the flange, a water jacket for the barrel connected with the said adapter member, and a manually operable latch on the casing adapted to engage the adapter to lock it in a predetermined position.

7. In an automatic firearm, the combination of a main casing having at its forward end a flange surrounding the barrel and adapted at its exterior to receive and engage an adapter for a water jacket, and a jacket for air cooling engaging the flange at the interior thereof.

8. In an automatic firearm, the combination of a main casing having at its forward end an interiorly threaded flange surrounding the barrel, the said flange being exteriorly threaded for the attachment of an adapter for a water jacket, and a barrel jacket for air cooling engaging the interior threads of the flange.

9. In an automatic firearm, the combination of a main casing having at its forward end a flange surrounding the barrel, a member engaging the exterior of the flange and adapted for connection with a gun mount, and a barrel jacket for air cooling engaging the flange at the interior thereof.

60

65

10. In an automatic firearm, the combination of a main casing having at its forward end a flange surrounding the barrel and threaded exteriorly and interiorly, a ring engaging the exterior threads of the flange and adapted for connection with a gun mount, and a barrel jacket for air cooling engaging the interior threads of the flange. 70

11. In an automatic firearm, the combination of a main casing having at its forward end a flange surrounding the barrel and threaded exteriorly and interiorly, a ring engaging the exterior threads of the flange and adapted for connection with a gun mount, a manually operable latch on the casing adapted to engage the connection ring to lock it in a predetermined position, and a barrel jacket for air cooling engaging the interior threads of the flange. 75 80

12. In an automatic firearm, the combination of a main casing having at its forward end a flange surrounding the barrel and threaded exteriorly and interiorly, a barrel jacket for air cooling adapted to engage the interior threads of the flange, an adapter for a barrel jacket for water cooling adapted to engage the exterior threads of the flange, and a connection member adapted to engage the said exterior threads interchangeably with the said water jacket. 85 90 95

13. In an automatic firearm, the combination of a main casing having at its forward end a flange surrounding the barrel and threaded exteriorly and interiorly, a barrel jacket for air cooling adapted to engage the interior threads of the flange, an adapter for a barrel jacket for water cooling adapted to engage the exterior threads of the flange, a connection member adapted to engage the said exterior threads interchangeably with the said water jacket, and a manually operable latch on the casing adapted to engage either the water jacket adapter or the connection member. 100 105 110
